UNITED STATES PATENT OFFICE.

VINCENZO DINI, OF BROOKLYN, NEW YORK.

DESIGN FOR A CENTER-PIECE.

SPECIFICATION forming part of Design No. 14,550, dated January 15, 1884.

Application filed August 7, 1883. Term of patent 7 years.

To all whom it may concern:

Be it known that I, VINCENZO DINI, of Brooklyn, in the county of Kings and State of New York, have invented a new and Improved Design for Center-Pieces for Ceilings, of which the following is a full, clear, and exact description.

Reference is to be had to the accompanying photograph, forming a part of this specification, and which is a plan view of my newly designed center-piece.

The leading feature of my design consists in a raised central ornament surrounded by an annular band of leaf-and-flower ornaments, and that surrounded by a rectangular band of leaf-and-stem ornaments having a raised circular ornament at each corner, and surrounded by an ornamental border or edge, the angular spaces between the annular and rectangular bands being filled with frosted work. In the center of the design is a raised ornament, which is surrounded by an annular band of leaf ornaments, arranged in shell shapes and having between them stalks of flowers. The annular band is surrounded by a rectangular band of leaf-and-stem ornaments, and having a raised circular ornament at each corner. The rectangular band is surrounded by an ornamental edge or border. The angular spaces between the annular and rectangular bands are filled with frosted work. At each side of the middle part of the center-piece is placed a side piece, formed of a scroll ornament arranged in shell shape, with series of balls drooping from stems arranged along the inner sides of the edges of the said ornament, and a stalk of flowers in its center. The side ornaments are surrounded with an ornamental edge or border corresponding with the edge of the rectangular middle part of the center-piece. The side pieces can be lengthened and shortened, to allow the center-piece to be used in

large and small rooms, and two of them may be made long and two short, to allow the center-piece to be used in oblong rooms, while retaining the same design. The latter arrangement is illustrated in the photograph.

Having thus described my invention, I claim as new and desire to secure by Letters Patent—

1. The design for a center-piece for ceilings herein shown and described, the same consisting of a raised central ornament surrounded by an annular band of leaf-and-flower ornaments, and that surrounded by a rectangular band of leaf-and-stem ornaments having a raised circular ornament at each corner, and surrounded by an ornamental border or edge, the angular spaces between the annular and rectangular bands being filled with frosted work.

2. The design for a center-piece for ceilings herein shown and described, the same consisting of a raised central ornament surrounded by an annular band of leaf-and-flower ornaments, and that surrounded by a rectangular band of leaf-and-stem ornaments having a raised circular ornament at each corner, and surrounded by an ornamental edge or border, the angular spaces between the annular and rectangular bands being filled with frosted work, and a scroll ornament arranged in shell shape, with series of balls drooping from stems arranged along the inner sides of the edges of the said ornament, and a stalk of flowers in its center placed at each side of the rectangular middle part of the design, and surrounded with an ornamental border or edge corresponding with the ornamental edge of the rectangular band.

VINCENZO DINI.
